UNITED STATES PATENT OFFICE.

JOHN EDWARD HITCH, OF WILMINGTON, OHIO.

DESIGN FOR A NAIL-SET OR COUNTERSINK.

SPECIFICATION forming part of Design No. 22,647, dated July 25, 1893.

Application filed June 13, 1893. Serial No. 477,495. Term of patent 14 years.

To all whom it may concern:

Be it known that I, JOHN EDWARD HITCH, a citizen of the United States, residing at Wilmington, in the county of Clinton and State of Ohio, have invented and produced a new and original Design for a Nail-Set and Countersink; and I do hereby declare the following to be a full, clear, and exact description of the same, reference being had to the accompanying drawings, forming a part thereof.

Figure 1 is a view in elevation of a nail-set and countersink embodying my design. Fig. 2 is a sectional view of the lower or nail-set end of the instrument.

A designates the shank, B the countersink which consists practically of a lateral enlargement of the shank in conical form, the base being turned upward.

C designates the nail-set which consists of a cylindrical prolongation of the apex of the conical countersink B.

The principal features of my design reside in the conical enlargement B constituting the countersink and the cylindrical prolongation C thereof.

What I claim, and desire to secure by Letters Patent, is—

The design for a nail-set and countersink, substantially as herein described and shown.

In testimony whereof I affix my signature in presence of two witnesses.

JOHN EDWARD HITCH.

Witnesses:

CHARLES M. JENKINS,
FRANK M. CLEVENGER.
